(57) **CLAIM**

The ornamental design for a hip thrust belt, as shown and described herein.

DESCRIPTION

FIG. 1 is a front perspective view of the hip thrust belt, showing our new design, with the belt folded;

FIG. 2 is a rear perspective view thereof;

FIG. 3 is a top plan view thereof; and

FIG. 4 is a bottom plan view thereof;

FIG. 5 is a front elevation view thereof;

FIG. 6 is a rear elevation view thereof;

FIG. 7 is a right-side elevation view thereof; and

FIG. 8 is a left-side elevation view thereof.

FIG. 9 is a front perspective view of the hip thrust belt, showing our new design, with the belt unfolded;

FIG. 10 is a top plan view thereof; and

FIG. 11 is a bottom plan view thereof;

FIG. 12 is a front elevation view thereof;

FIG. 13 is a rear elevation view thereof;

FIG. 14 is a right-side elevation view thereof; and,

FIG. 15 is a left-side elevation view thereof.

The broken lines are for environmental purposes only and form no part of the claimed design.

1 Claim, 9 Drawing Sheets
